[57] **CLAIM**

The ornamental design for combined plush animal handbag set, as shown and described.

DESCRIPTION

FIG. 1 is a front elevational view of a combined plush animal handbag set showing my new design;
FIG. 2 is a left side elevational view thereof;
FIG. 3 is a right side elevational view thereof;
FIG. 4 is a top plan view thereof;
FIG. 5 is a bottom plan view thereof;
FIG. 6 is a rear elevational view thereof; and,
FIG. 7 is a top plan view thereof, similar to FIG. 4, but illustrating the use of hook and loop fastening means to enable separation of the plush animals.

FIG.1

FIG. 2

FIG. 3

FIG.4

FIG. 5

FIG. 6

FIG. 7
